DESIGN FOR A STEERING WHEEL

Felix J. Kathe, Cleveland, Ohio

Application October 16, 1937, Serial No. 72,219

Term of patent 3½ years

To all whom it may concern:

Be it known that I, Felix J. Kathe, a citizen of the United States of America and a resident of Cleveland, in the county of Cuyahoga and State of Ohio, have invented a new, original, and ornamental Design for a Steering Wheel, of which the following is a specification, reference being had to the accompanying drawing, forming part thereof.

In the drawing, Figure 1 is a plan view of the steering wheel, showing my design; and Figure 2 is a side elevational view of the steering wheel shown in Figure 1.

I claim:

The ornamental design for a steering wheel, as shown.

FELIX J. KATHE.
